UNITED STATES PATENT OFFICE.

MARTIN BAILER, OF CHICAGO, ILLINOIS.

ADJUSTABLE SCAFFOLD AND DERRICK.

No. 923,002.

Specification of Letters Patent.

Patented May 25, 1909.

Application filed March 3, 1908. Serial No. 419,040.

To all whom it may concern:

Be it known that I, MARTIN BAILER, citizen of the United States, residing at Chicago, in the county of Cook and State of Illinois, 5 have invented certain new and useful Improvements in Adjustable Scaffolds and Derricks, of which the following is a specification.

This invention is an adjustable scaffold 10 and derrick particularly adapted for building smoke-stacks, tanks and upright tubes of various kinds, and is useful especially when such structures are made of iron rings or sections which are bolted to each other.

15 The object of the invention is to provide an improved device of the kind having simple and efficient means for supporting the scaffold within the stack or other structure. A derrick is mounted on the scaffold, where- 20 by the successive sections and other material may be hoisted, the hoisting rope passing down through the stack and being operated by a hoisting engine or the like on the ground. The scaffold can be quickly raised from one 25 position to another as the stack or other structure is built up.

The invention is illustrated in the accompanying drawings, in which—

Figure 1 is a vertical section of the invention. Fig. 2 is a top plan view of the scaffold. Fig. 3 is a section on the line 3—3. Fig. 4 is a plan of the braces for the scaffold.

Referring specifically to the drawings, Fig. 1 shows the apparatus ready for use and set 35 inside of a section 1 of a smoke-stack being built. The scaffold has a center casting 2 having ears 3 on the outer side to which six (more or less) legs 5 are pivoted by bolts 4. These legs or supports extend downwardly 40 and outwardly and are made of flat bar iron twisted at their lower ends and sharpened, as indicated at 11, so as to rest upon the rim or top of the lower stack section 12, pressing against the inside of the stack section 1.

45 These supports are held in extended position by means of wires 13 connected at their lower ends thereto and having coiled springs 14 at their upper ends, which are fastened to hooks 15 the threaded ends of which extend through the lower flange of an upper ring 16 of angle iron, and held there by nuts 17. By adjusting the nuts the tension on the springs 50 may be varied as desired. The springs tend to extend the supports and cause the same to press against the sides of the stack, whereby they are prevented from slipping off the edge

of the lower stack section, and are also caused to automatically engage the same when the scaffold is raised to the next section. The whole scaffold and derrick are 60 supported by these legs 5.

At the center is a pipe 18 the lower end of which is expanded into a socket in the casting 2 and the upper end of which is provided with a horizontal ring flange 19. On this 65 ring flange is bolted a ring plate 20, and also the inner ends of radial angle bars 21 the outer ends of which are bolted to the outer ring 16 above referred to. A ring 23 is fastened to or clamped around the pipe 18, near 70 the lower end thereof, and extending between this ring and the horizontal bars 21 are braces 24 which are conveniently made of T-iron and are secured by bolts 25. These braces serve to maintain and support the scaffold, 75 the scaffold boards or flooring 38 being laid upon the bars 21. Blocks 26 are riveted or otherwise fastened to the ring 16, conveniently at the outer ends of the bars 21, and set screws 27 pass through these blocks and 80 are adapted to be screwed against the side of the stack section 1 to hold the scaffold steady and in place when in use. When the scaffold is to be raised the set screws are loosened.

The ring plate 20 forms an upper bearing 85 for the tubular derrick standard 28, the foot of which is stepped loosely in a bearing socket in the casting 2. The derrick standard can be turned in a full circle. It carries at its upper end the blocks 29, 30 and 31, 90 over the wheels of which the hoisting rope 32 passes, and extends through a slot 34 in the standard and down through the same and through a hole 35 in the casting 2, and thence through a block 36 at the base of the stack 95 and out to the hoisting engine or windlass. The top of the derrick standard overhangs so that all material for building the stack may be hoisted on the outside thereof and received onto the scaffold platform. When 100 the scaffold is in place the upper section 37 of the stack can easily be riveted to the section 1, and when said upper section is completed the set screws 27 are loosened and the whole device hoisted by any suitable means, 105 as by a block and tackle hung on the upper rim of the section 37 or on timbers laid across the top thereof. When the legs 5 reach the top of the section 1 they will snap out over the same and catch thereon, and the scaffold 110 will be ready to build another section. In this manner the scaffold can be raised as fast

as the stack or other structure is constructed.

I claim:

1. In a scaffold, the combination of a central block or piece, a series of radial legs hinged thereto and arranged to swing out to engagement with a stack or the like, an upright mounted on said block, a platform supported by said upright at the top thereof, and braces between the upright and the outer parts of the platform.
2. The combination of a platform, means to support the same at various positions in a stack or the like, and a derrick mounted upon the platform and having a hoisting rope extending down through the platform.
3. The combination of a platform, means to support the same in a stack or the like, and a rotary derrick having a tubular stand-

ard mounted on the platform and a hoisting rope extending down through the standard and the platform.

4. The combination of a central block or casting, legs connected thereto and arranged to engage the side of a stack or the like, a tubular upright on said casting, a platform supported on said upright, and a derrick having a standard resting on said casting and extending upwardly through the upright and the platform.

In testimony whereof I affix my signature, in presence of two witnesses.

MARTIN BAILER.
